(57) **CLAIM**

The ornamental design for an ashtray, as shown and described.

DESCRIPTION

FIG. 1 is a top perspective view of an ashtray, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a partial enlargement of FIG. 1; and,

FIG. 10 is a usage state view thereof.

The broken lines consisting of evenly spaced dash lines in the drawing depict portions of the Ashtray that form no part of the claimed design; The broken lines consisting of short and long dash lines encircling the enlarged detail views are for annotative purposes that form no part of the claimed design.
